UNITED STATES PATENT OFFICE

2,411,813

METHOD AND APPARATUS FOR MANUFACTURE OF WIRE FASTENERS

Conrad B. Schwarz, Louisiana, Mo.

Original application October 7, 1941, Serial No. 413,997, now Patent No. 2,357,290, dated September 5, 1944. Divided and this application January 5, 1944, Serial No. 517,052

2 Claims. (Cl. 140—93)

1

This invention relates to a process and apparatus for manufacturing a cover fastener. More particularly, this invention relates to a process and apparatus for manufacturing a new and improved wire fastener attached to the slatted cover of a bushel basket, or the like.

It is the usual practice to provide baskets of the bushel type with a pair of wire handles projecting upwardly above upper edge of the basket. Such baskets usually have a slatted cover with a top slat elongated so that its projecting ends engage in said basket handles. It has become the practice in packing these baskets to have them heaping full; hence, difficulty is encountered in fastening the cover to the basket so as to provide a satisfactory fit. These covers are under a bulging strain which brings about a need for additional fasteners besides the two furnished by the handle and the elongated slat. Such additional fasteners may be termed side fasteners and are usually used in pairs, one fastening to the basket and the other to the cover. Slatted covers of this type are usually assembled with the wire side fasteners affixed thereto so that when the cover is ready for attaching to the basket this can be accomplished with little loss of time.

With the fasteners now in use, difficulty is encountered in attaching the side fasteners affixed to the basket to the side fasteners affixed to the cover. In order to overcome this difficulty, fasteners have been made which protrude over the edge of the cover. However, in view of the fact that the covers are shipped in bundles, such protruding fasteners become bent out of shape by blows received during shipment and, as the wire fasteners must necessarily be made of a relatively stiff wire, the straightening of these fasteners requires considerable time as well as the use of mechanical instruments such as pliers. Moreover with side fasteners of this type considerable trouble has been experienced in the fasteners splitting the slats of the cover, and the cover becoming loose after the basket is packed. It is evident that any improvement that may be made in these side fasteners, which will overcome all of these difficulties, will provide a marked advance in the art.

This invention has as its object to provide a new and improved wire fastener. Another object is to provide a new and improved protruding wire side fastener to be attached to a slatted cover for bushel baskets, or the like. Still another object is to provide a protruding wire fastener of stiff wire, which, when deformed, may be easily restored to its original position without having to resort to

2

the use of pliers and the like. Another object is to provide a new and improved wire fastener for a slatted cover which in use will strengthen the cover and prevent the splitting of the slats. Another object is to provide a process for the manufacturing and attaching of such improved wire fasteners. Still another object is to provide a machine for the manufacturing and the attaching of such wire fasteners. Other objects will be apparent from the following description of the invention.

These objects are attained with the construction and by means of the apparatus shown in the accompanying drawings and described herein.

15 Figure 1 is a top view of a slatted cover with the improved fasteners side at points along the rim midway between the ends of the elongated top slat.

Figure 2 is an end view of a fragmentary portion 20 of said cover, facing said improved fastener, with a fragmentary portion of the basket and the fastener attached to said basket.

Figure 3 is a vertical sectional view through the 25 middle of the fragmentary portion of said cover and basket and the fasteners shown in Figure 2. The tongue member, that is the portion attached to the basket, is shown in full lines in the inserted position and in dotted lines in the locking position.

Figure 4 is a fragmentary top view of said cover 30 showing the improved fastener in proper position in full lines and in the damaged position in dotted lines.

Figure 5 is an enlarged, fragmentary top view 35 showing the improved fastener in the damaged position.

Figure 6 is a vertical, cross sectional view through the middle of the fastener shown in Figure 5.

Figure 7 is an enlarged, fragmentary top view 40 of the fastener in proper position.

Figure 8 is a vertical, cross sectional view through the middle of the fastener shown in Figure 7.

Figures 9, 10, and 11 are cross-sectional, perspective drawings of the parts of the machine fastener and of the cover during the various stages of attaching the fastener to the cover.

Figure 12 is a perspective view of the machine which forms the wire fastener in to shape prior to attaching same to the cover, said parts being in their near relative position, and separated sufficiently to show the shape of each part and to indicate its operation.

In Figures 1 to 8, inclusive, the reference numbers in each figure refer to the same parts of the

structure. The reference number 1 indicates the slatted cover. The reference number 2 indicates the basket. The cover 1 is constructed of wooden slats 3 with an elongated top slat 4 having projecting ends for the purpose of engaging in the handles (not shown) of the basket 2. The cover has a marginal hoop 5 to which the slats are attached. Midway between the elongated ends and the slat 4 on the marginal hoop 5, the cover is provided with the new and improved protruding wire fastener 6. This fastener 6 has a protruding loop 7 which in its normal, usable position, protrudes over the edge of the cover. This loop may be squared as shown or may have rounding edges and need not be affixed to the midway point, but may be affixed at any point along the marginal hoop 5 between the protruding ends of the slat 4. The fastener has two arms, 8, which extend in opposite directions from the end of the loop 7. The right arm (looking at Figure 4) may be at an angle between 45° and 90° clockwise from a line parallel to and representing an extension of the right side of said loop and the left arm may be at an angle between 270° and 315° clockwise from a line parallel to and representing an extension of the left side of the loop 7. It is preferable that the arms 8 extend in lines approximating that of the hoop 5. As they are relatively straight, they are of such an angle to each other that they will be tangent to the circumference of a circle having a diameter not greater than hoop 5 and not less than one-half the diameter of said hoop when the fastener is in its normal position. In Figure 4 the fastener 6 is shown in its normal position by the drawing in solid lines, and in sprung back position by the drawing in dotted lines. This sprung position results when the loop strikes an obstruction such as the floor, at the time the covers are being shipped, or when they are stacked on edge. Figures 5 and 6 also show, in an enlarged form, the fastener 6 in a sprung back position, while Figures 7 and 8 show the fastener 6 in its normal position.

Referring to Figures 7 and 8, the arms 8 of the fastener 6 extend at least half-way across each of the two slats 3. If only one slat is used instead of two, they may extend practically across the entire slat. These extended arms, when the cover is in use, pull down across the top of the slat, preventing the slat from coming loose from the marginal hoop 5. As they pull across grain, they do not tend to split the slat. The fastener 6 with the extended arms 8 may be attached to the cover by any conventional method. Figure 8 shows a method found to be commercially practical. Here the wire extends downward through the slat 3 on the inside of the hoop 5—see 9—across the bottom of the hoop 5—see 10—and part way up the outside of the hoop 5—see 11.

The combination of the protruding loop with the extended arms forms a fastener which, when deformed or sprung back as shown in Figure 5, may readily be pulled into the usable position of Figure 7 without the use of pliers or other mechanical instruments, regardless of how stiff the wire is. The wire from which these fasteners are to be made is preferably of a gauge within the range of 14 to 17 and of the type known as bright stapling wire when the fasteners are to be used on slatted covers for bushel baskets, or the like.

Figures 2 and 3 show the fastener in use. The tongue-like fastener 12 attached to the basket 2 passes up through the loop 7 of the cover fastener

6 and is bent back as shown by the dotted lines in Figure 3.

Referring to Figure 12, the parts in this drawing are in their near relative position, separated just sufficiently to show the shape of each part clearly. DL and DR fit against the ends of C and EL and ER slide down over the fins on DL and DR. The fins on D and the grooves in E are the same size as the size of wire used to make the fastener. W represents the wire feed into the machine from the right. A is the cutter which advances with BL and BR striking the wire first and cutting off the correct length to make one fastener. BL and BR carry the wire against C, causing the wire to bend first into the shape of L1. When BL and BR are fully advanced they force the wire tightly against the shoulder on C, DL and DR forming the shape shown by L2. EL and ER then descend, bending the ends of the wire down over the edges BL and BR to form the final shape of the fastener, before being driven into the cover, as shown by L3. BL and BR then recede, leaving the fastener supported by C, DL, DR, EL and ER. When BL and BR are in the clear the cover is brought up from below as is shown by Figures 9, 10, and 11.

In Figure 9, T represents the table or anvil of the machine into which is placed two inserts designated by I, one for each leg of the fastener, and through which two clinch pins, designated by P, can raise from below. The cover W is placed over the insert I by the operator of the machine. T raises, taking I and P in the same relative position with it, until it reaches the position shown in Figure 10. As is shown by drawing, the leg of the fastener L is driven through the cover slat 3 past the hoop 5 and guided across below the hoop and into the slot above P. This is done by the shape of the groove in the face of I. This groove is shown by the dotted line in Figure 9. When I and W strike C, a latch releases and T remains stationary while P continues to advance to position shown by Figure 11. This rolls the end of the loop tight around the bottom of the cover hoop 5. There is a groove in P, shown by dotted line, to allow the wire to pass when the pin slides up against the cover hoop 5. A small kick off is provided to kick the loop loose from the end of C and, when T retards, the cover is taken from the machine by the operator. In this manner the new and improved wire fastener is made and attached to the cover.

As many apparently widely different embodiments of this invention may be made without departing from the spirit and scope thereof, it is to be understood that this invention is not to be limited to the specific embodiments shown and described.

This application is a division of my copending application Serial No. 413,997, filed October 7, 1941, for Wire fastener and method and apparatus for manufacture, now U. S. Patent No. 2,357,290, issued September 5, 1944.

I claim:

1. A method of forming and attaching a protruding wire side fastener to the top of a slatted cover for a bushel basket or the like which comprises cutting a piece of wire to proper length, causing the wire to bend so as to form a V-like shape with a flat base, forcing the flat base between two parallel plates in a direction parallel to the surfaces of said plates, said base being held perpendicular to said surfaces thereby forming a U-shaped loop at the vertex of the angle made by the V-shaped arms, bending the ends of the

arms in an opposite direction but horizontal position while maintaining the entire shape in one plane, then bending the ends of the arm downward perpendicular to said plane, forcing the perpendicular ends through the top of the slatted cover adjacent to the inner circumference of its marginal hoop and bringing said ends under and around said marginal hoop to the outside, thereby fastening said wire-wide fastener to said cover.

2. A machine for forming and attaching a new and improved wire fastener to a slatted cover for a bushel basket or the like which comprises in combination a cutter, means for bending a wire so as to first form a V-like shape with a flat base, means for forcing the wire between two plates with parallel surfaces in a direction parallel to said surfaces while holding the base perpendicular to said surfaces, thereby forming a U-like loop at the vertex of the angle formed by the

5 V-like arms, means for bending the ends of said arms first into a horizontal position whereby they extend in opposite directions and the entire shape is in one plane and then bending said ends downward along the line perpendicular to said plane, means for holding said shaped wire fastener in a stationary position with the ends of each arm projecting downward, an anvil shaped so as to hold in position a slatted cover and provided with two clinch pins designed so that they may be raised from below, means for raising the anvil so that the ends of the wire fastener may be driven through the slatted cover, means for then bringing up the clinch pins from below so as to clinch the wire around the marginal hoop of said slatted cover, thereby fastening said wire fastener to said cover.

CONRAD B. SCHWARZ.
